UNITED STATES PATENT OFFICE.

CHARLES O. MICHAELSEN, OF OMAHA, NEBRASKA.

ORE CLASSIFIER AND CONCENTRATOR.

1,126,819.

Specification of Letters Patent.

Patented Feb. 2, 1915.

Application filed January 24, 1914. Serial No. 814,228.

To all whom it may concern:

Be it known that I, CHARLES O. MICHAELSEN, a citizen of the United States, and a resident of Omaha, in the county of Douglas and State of Nebraska, have invented certain new and useful Improvements in Ore Classifiers and Concentrators, of which the following is a specification.

My invention relates to ore washing, separating, classifying and concentrating machines.

It is the object thereof to provide a machine adapted to handle large quantities of ore containing, together with rock, gravel, sand or the like, a certain proportion of valuable mineral constituents in finely divided form and of greater specific gravity than the valueless constituents; the machine being adapted to classify or separate the material into two parts of which one will contain practically all of the valuable material; so that the bulk of material to be handled subsequently by other machines, or to be directly smelted or refined, will be greatly reduced.

A machine embodying my invention is illustrated in the accompanying drawings, in which—

Figure 1 is a longitudinal vertical section thereof, Fig. 2 is a plan view of the same, with certain parts broken away to show the interior, Fig. 3 is a transverse vertical section on the plane of the line $x-x$ of Fig. 1, Fig. 4 is a detail end view of a part of the cradle device, and Fig. 5 is a detail plan view of a part of the cradle actuating means, with parts broken away.

In the construction of the machine illustrated, I provide a horizontal tubular main shaft 1 which is journaled in suitable bearings 2 carried in standards 3, 4 and 5. Said standards are mounted on suitable foundations such as blocks 6 of concrete. In the upper part of the standards 4 and 5 is journaled a drive-shaft carrying at its ends flying wheels 7 which may be employed as pulleys and connected by belt with a suitable source of power. On the central part of the drive-shaft is a pinion 8 which meshes with a gear 9 carried by a shaft journaled in the intermediate parts of the standards. The gear 9 meshes with a gear 10 mounted concentrically with the tubular shaft 1 on a hub-body 11 secured to said shaft as shown. The gears 9 and 10 carry interfering rollers 12, and the gear 10 and hub-body 11 are yielding connected to each other, all in the man-

ner shown and fully described in Letters Patent No. 1,085,751, issued to me February 3, 1914, for interrupted drive gearing. By said drive gearing, continuous rotary movement imparted to the drive-shaft, pinion 8 and gear 9, causes an intermittent or alternately retarded and accelerated rotary movement of the tubular shaft 1.

On the end of the bearing 2 carried by the standard 5 is secured an annular plate 13 with which is connected a feed-pipe 14 of which the end extends into the tubular shaft as shown. The materials to be operated upon by the machine are supplied through the pipe 14, together with a suitable quantity of water.

In the tubular shaft at some distance beyond the end of the feed-pipe 14 is a plug 15, and in the sides of the shaft between the plug and the end of the pipe are ports 16 through which the material supplied through the feed-pipe escapes from the shaft into a distributing-chamber 17. Said chamber is formed within a shell 18 of which one end is carried upon an end-plate 19 secured to the shaft near the bearing-standard 4, and the other end is carried upon a spider 20 secured upon the shaft as shown. The shell 18 is frusto-conical in form, being smallest in diameter at the end-plate and largest at the spider, so that the lower side of the shell is slightly inclined downwardly from the end-plate to the spider. The one end of the distributing-chamber is closed by the end-plate 19 and the other end of the chamber is partly closed by a circular baffle or check-plate 21. The latter has a hub-portion which fits slidably on the shaft and is adjustable longitudinally thereon to vary the capacity of the distributing-chamber. The diameter of the check-plate is less than the internal diameter of the shell 18, so that an annular opening or port is left between the shell and the edges of the plate. Owing to the tapering or conical form of the shell the width of said annular port is varied more or less by adjustments of the check-plate longitudinally of the shaft.

To the end of the shell 18 adjoining the spider 20 is connected a shell, having a conical portion 22 of which the smaller end fits over the end of the shell 18, and a cylindrical portion 23 integral with the conical portion and extending horizontally from the larger end of the conical portion.

Adjoining the open end of the cylindrical

shell-portion 23 is a ring 24 having a conical flange, or annular outwardly flaring lip, 25 of which the outer diameter is the same as the internal diameter of the cylinder 23. 5 The ring 24 is carried on a spider 26 which is slidably longitudinally on the shaft 1.

To the hub of the spider is secured a threaded sleeve 27 which is engaged by an internally threaded collar 28. The other 10 end of the collar 28 engages a second threaded sleeve 29 secured to the hub of a check-plate 30 which is fixedly secured to the shaft 1 adjacent to the bearing-standard 3, as shown. The threads of the opposite ends of 15 the collar 28 and of the respective collars 27 and 29 are opposite in direction. The collar has in its outer surface suitable openings for engagement by a spanner-wrench, by which the collar may be turned to adjust the position 20 of the spider 26 and ring 24 longitudinally of the shaft 1.

The space 31 within the cylindrical shell-portion 23 will be herein designated as the cradle-chamber. Within said chamber on 25 the shaft 1 is secured a sleeve 32. A spline 33 in one side of the shaft 1 extends through said sleeve, and through the hubs of the check-plate 30, the spider 26, the spider 20, the check-plate 21 and end-plate 19, securing 30 all of said parts against rotary movement relatively to the shaft. Around the sleeve 32 is disposed a collar comprising a lower body-portion 34 and a separable cap-portion 35, and between said collar and the 35 sleeve 32 is arranged a roller-bearing 36. The cap 35 is provided with an oil-cup 37 for lubricating the bearing.

In the lower body-portion 34 of the collar are several longitudinal openings in 40 which rods 38 are secured by means of the set-screws 39. Said rods emerge from the end of the collar adjacent to the spider 20, curve downwardly in planes radial to the shaft 1, and have end-portions 40 which 45 extend horizontally adjacent to the inner surface of the cylindrical shell-portion 23. The rod-portions or arms 40 are preferably flattened in planes radial to the shaft, as shown in Fig. 3. The several rods and the 50 collar, taken together, constitute a swinging cradle or agitating device, which is retained by gravity within the lower part of the cradle-chamber, the weight of the rods and of the lower body-portion of the collar 55 causing the collar to remain relatively stationary while the shaft and sleeve 32 revolve within it.

As a further means of retaining the cradle within the lower part of the chamber, there 60 is provided at the side of the collar, adjacent to the upwardly moving side of the shell 23, an arm 41 on which a counter-weight 42 is adjustably secured, as shown in Fig. 3.

65 In order to impart a certain oscillating

movement to the cradle, yielding actuating means are provided for intermittently swinging the same in the direction of rotation of the shaft 1, said yielding actuating means becoming disconnected intermittently as the resistance to such movement of the cradle exceeds a predetermined amount. Said actuating means are as follows: On one end of the cradle-collar formed by the parts 34 and 35 is secured a plate 43 on the face of which are a plurality of V-shaped lugs 44. A plate 45 having similar lugs 46 thereon is held slidably on the sleeve 32 by a short spline or key 47, the lugs on the two plates being on the adjoining sides thereof, as shown in Fig. 5. A helical spring 48 engages the plate 45 to push the same toward the plate 43, the spring being inclosed by a casing-tube 49 and said casing-tube being carried by and integral with a collar 50 which is fixedly secured to the sleeve 32. On the end of the sleeve 32 adjoining the spider 20 a thrust-collar 51 is secured to the sleeve, and between said collar and the end of the cradle-collar is a ball thrust-bearing 52. The pressure of the helical spring 48 against the plate 45 holds the lugs 44 and 46 normally in interengaging position, the longitudinal pressure upon the cradle-collar being received by the ball thrust-bearing and the collar 51. As the shaft 1 and sleeve 32 are revolved the inclined faces of the lugs engage each other so that the plate 45, being actuated by the key 47, tends to rotate the cradle with the 100 shaft. As the cradle swings upwardly, however, the weight thereof offers a progressively increasing resistance to the movement, which causes the spring 48 to be compressed by the longitudinal pressure on the plate 105 45 resulting from the pressure of the inclined faces of the lugs 44 upon the similar faces of the lugs 46. Finally, a position of the cradle is reached at which the resistance is such that the compression of the spring 110 48 will be sufficient to allow the adjacent pairs of the lugs 44 and 46 to slip past each other. The cradle then swings downwardly until the lugs again come into contact with each other, whereupon the upward swinging 115 movement is again commenced.

In the use of the machine the ring 24 is adjusted to a position on the shaft 1 such that the outer edge of the conical lip 24 is very close to the end of the shell 23, a narrow annular slit being left between them, the width of the slit being as best suited to the materials operated upon. The material fed into the distributing-chamber 17 through the pipe 14 and ports 16, escapes from the distributing-chamber through the annular port formed around the peripheral edge of the check-plate 21, and passes into the lower part of the cradle-chamber, filling said chamber to a level slightly above that 130

of the lower side of the ring 24. Within the cradle-chamber the material is constantly agitated by the intermittent or alternately retarded and accelerated rotary movements 5 of the shell, caused by the interrupter drive-gearing therefor. A further agitation of the material is caused by the oscillating movements of the cradle-arms 40 which pass longitudinally through the mass of material 10 as represented in Fig. 3, and which open up passages through the same which facilitate the descent of the heavier materials to the bottom of the mass. The heavier and more valuable material, which, in the class of materials operated upon by the machine, is mostly 15 in a finely divided state, passes out through the annular slit between the lip 25 and the end of the shell 23, being received in a suitable trough or chute 53, as shown in Fig. 26 1. The rock and the like, being lighter and also being mainly in larger pieces, remains at the top of the mass of material in the cradle-chamber, and passes out over the barrier formed by the lip 25, and through the 25 discharge opening provided by the open end of the ring 24, being received in a trough or chute 54 disposed below the end of said ring.

In addition to the water supplied with the 30 material through the feed-pipe 14, it is desirable to have a quantity of water supplied directly to the cradle-chamber. For this purpose a water-pipe 55 is inserted between the check-plate 30 and the end of the ring 35 24, said pipe having at its end a bent nozzle 56 adapted to direct a stream of water A against the side of the cradle-chamber on the upwardly-moving side of the shell, as represented in Figs. 2 and 3. The stream 40 directed to this point also serves to wash the material down into the bottom of the chamber and prevents it being carried up by the rotating shell. In order to interfere as little as possible with the water-stream A, the 45 arms of the spider 26 are made oval in section, but quite flat, and with their greatest thickness in planes parallel with the main shaft.

Now, having described my invention, 50 what I claim and desire to secure by Letters Patent is:

1. In a machine of the class described, a horizontally disposed cylindrical shell, actuating means for intermittently rotating 55 the shell, an annular barrier partly closing one end of the shell, there being a narrow annular aperture between said barrier and the end of the shell, means for feeding materials into the end of the shell opposite the barrier, and means for agitating the materials in the lower portion of the chamber within the shell.

2. In a machine of the class described, a horizontal revolvably mounted shaft, means 60 for revolving the same intermittently, a cy-

lindrical shell carried by the shaft concentrically therewith, a ring of smaller diameter than the shell and carried by the shaft adjacent to an open end of the shell, a conical lip on the ring extending into close proximity to said end of the shell so that a narrow annular aperture is formed between them, and means for feeding materials into the shell.

3. In a machine of the class described, the 75 combination with a horizontally disposed cylindrical shell, and actuating means for revolving the same with an alternately retarded and accelerated movement, of a ring smaller in diameter than the shell and disposed concentrically therewith adjacent to an open end thereof, a lip on the ring extending toward the end of the shell so that a narrow annular slit is left between them, 80 agitating means within the shell, means for feeding materials into the shell, and means substantially closing the end of the shell opposite the ring.

4. In a machine of the class described, an intermittently rotating cylindrical shell disposed on a horizontal axis, a tubular shaft extending through the shell, means for feeding materials through the tubular shaft into one end of the shell, a barrier concentric with the shell for partially closing the other 95 end of the same, there being a uniform annular opening between said barrier and the end of the shell, and means for adjusting said barrier longitudinally of the shaft to vary the width of the annular opening.

5. In a machine of the class described, a horizontal rotating shaft, means for actuating the same intermittently, a substantially cylindrical casing carried thereby, said casing being partially open at one end and having an annular slit in its peripheral portion adjacent to said end, means for feeding materials into the casing, and a swinging cradle carried on the shaft within the casing and having arms extending into the lower part 100 thereof for agitating materials therein.

6. In a machine of the class described, a horizontally disposed substantially cylindrical casing having one end partially open and an annular peripheral aperture adjoining said end, means for revolving said casing with an alternately retarded and accelerated movement, a swingable cradle carried within the casing and having parts extending along the lower peripheral part 115 thereof, means for feeding materials into the casing, and means for oscillating the cradle.

7. In a machine of the class described, a horizontally disposed rotating shaft, a substantially cylindrical casing carried thereon, the casing being partially open at one end and having a peripheral aperture adjoining said end, a cradle having a plurality of arms extending into the lower part of the 125 130

casing and carried on the shaft so as to be swingable thereon, means for feeding materials into the casing, yieldable actuating means carried on the shaft and engaging the cradle to swing the same upwardly from a normal dependent position, and a counterweight on the cradle for controlling the resistance thereof to the yielding actuating means.

10 8. In a machine of the class described, a horizontal revoluble substantially cylindrical casing having two discharge openings concentric therewith, one of said openings being of smaller radius than the other whereby a part of the latter opening will be

constantly at a lower level than any part of the first, means for revolving the casing with an alternately retarded and accelerated movement, means for feeding materials into the same, and suspended oscillating agitating means normally positioned in the lower part of the casing. 20

In testimony whereof I have hereunto subscribed my name in the presence of two witnesses.

CHARLES O. MICHAELSEN.
